US0D1002662S

(12) **United States Design Patent** (10) Patent No.: **US D1,002,662 S**
(45) Date of Patent: ** Oct. 24, 2023

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US); **Erica L. Clymer**, Northampton, PA (US); **Shenchi Tian**, Easton, PA (US)

(73) Assignee: **Lutron Technology Company LLC**,
Coopersburg, PA (US)

(**) Term: **15 Years**

(21) Appl. No.: **29/844,102**

(22) Filed: **Jun. 27, 2022**

Related U.S. Application Data

(63) Continuation of application No. 29/780,927, filed on Apr. 27, 2021, now Pat. No. Des. 959,470, which is a continuation of application No. 29/707,327, filed on Sep. 27, 2019, now Pat. No. Des. 920,360, which is a continuation of application No. 29/663,983, filed on Sep. 20, 2018, now Pat. No. Des. 866,588, which is a continuation of application No. 29/607,668, filed on Jun. 15, 2017, now Pat. No. Des. 830,409.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.

**1 Claim, 1 Drawing Sheet
(1 of 1 Drawing Sheet(s) Filed in Color)**
